UNITED STATES PATENT OFFICE.

JOHN A. SHOEMAKER, OF LA SALLE, NEW YORK.

BUTTON-POLISHING MACHINE.

SPECIFICATION forming part of Letters Patent No. 664,101, dated December 18, 1900.

Application filed July 11, 1900. Serial No. 23,252. (No model.)

To all whom it may concern:

Be it known that I, JOHN A. SHOEMAKER, a citizen of the United States, residing at La Salle, in the county of Niagara and State of New York, have invented new and useful Improvements in Button-Polishing Machines, of which the following is a specification.

This invention relates to a machine for buffing or polishing buttons, and embraces in its general organization a buffing-wheel whereby the buttons are buffed or polished, a carrier provided with dies which support the buttons, and a dust-discharge pipe whereby the dust removed from the buttons is carried away.

One of the objects of this invention is to improve the mechanism for rotating the dies which carry the buttons and the carrier upon which the dies are mounted.

Another object of this invention is to improve the construction of the dies and the carrier supporting the same.

Another object of my invention is to provide simple means for retaining the buttons on the dies preparatory to polishing the same and also to remove the same from the dies after being polished.

Another object of my invention is to improve the means for adjusting the buffing-wheel.

Another object of my invention is to provide simple means for automatically applying wax to the buffing-wheel.

My invention has the further object to improve the machine in several details of construction.

In the accompanying drawings, consisting of four sheets, Figure 1 is a side elevation of my improved button-buffing machine. Fig. 2 is a fragmentary horizontal section in line 2 2, Fig. 1, showing the device for adjusting the button-ejector. Fig. 3 is a central longitudinal sectional elevation of my improved buffing-machine, taken in line 3 3, Fig. 6. Fig. 4 is a fragmentary horizontal section in line 4 4, Fig. 3, showing part of the device whereby wax is applied to the buffing-wheel. Fig. 5 is a fragmentary vertical section in line 5 5, Fig. 4. Fig. 6 is a vertical transverse section of the machine, taken substantially in line 6 6, Fig. 1. Fig. 7 is a fragmentary vertical section, on an enlarged scale, of one of

the button-supporting dies or holders. Fig. 8 is a fragmentary horizontal section in line 8 8, Fig. 6. Fig. 9 is a fragmentary vertical section in line 9 9, Fig. 1. Fig. 10 is a top plan view of the machine with the dust-discharge pipe shown in section. Fig. 11 is a fragmentary horizontal section in line 11 11, Fig. 6, showing the plate whereby the buttons are confined on the dies. Fig. 12 is a similar section in line 12 12, Fig. 1, showing part of the device whereby the buffing-wheel is adjusted backward and forward. Fig. 13 is a fragmentary vertical section showing the means for polishing different sizes of buttons on the same spindles.

Like letters of reference refer to like parts in the several figures.

The main frame of the machine consists, essentially, of a base A and two standards A' A'', mounted on the base.

B represents the rotary buffing-wheel, of soft material, whereby the buttons are buffed or polished and which is mounted on a horizontal shaft B'. The dies C, which support the buttons while being polished, are mounted on a rotary carrier D, arranged with its rear portion below the buffing-wheel and mounted on an upright carrier-shaft E. The carrier consists of upper and lower journal-disks d d', connected by a hub d'', which is secured to the carrier-shaft, and a supporting-plate d'', mounted loosely on the carrier-shaft above the upper journal-plate and resting on the latter. Each of the dies consists of a vertical spindle c and a ring or sleeve c'', surrounding the upper end of the spindle. The upper end of the spindle forms the bottom of the die, and this end of the spindle is preferably concaved, as shown at c', Fig. 7, so as to receive the convex under side of the buttons. When the die spindle and sleeve are in their proper relative position, the spindle is depressed, so that the upper part of the die-sleeve projects above the upper end of the spindle, thereby forming the side wall of the die, as shown at c'', Fig. 7. While the parts of the die are in this position, the operator places a button upon the same, which button rests with its under side on the spindle and with its edge against the inner side of the die-rim, whereby the button is confined upon the die while being carried past the

buffing-wheel, and the projecting upper part of the button is polished by the wheel.

When it is desired to polish buttons of larger diameter, the small die-ring is replaced by a larger one corresponding to the size of the button to be polished, and a spacing-ring c^4 is interposed between the die-spindle and the large die-ring, as shown in Fig. 13.

The carrier-shaft is journaled near its upper and lower ends in bearings e^e' , arranged on the front side of the standard A' , and is driven from a horizontal driving-shaft F , arranged below the carrier-shaft, by a pair of intermeshing bevel gear-wheels f^f' , mounted, respectively, on the driving-shaft and the lower end of the carrier-shaft. The gear-wheel f is splined on the driving-shaft, so as to permit the same to move lengthwise thereon, thereby enabling the gear-wheels f^f' to be engaged or disengaged for rotating the die-carrier or stopping the rotation thereof. The driving-shaft is provided at its outer end with a driving-pulley e^2 , which receives a driving-belt. The die-spindles are arranged in an annular row around the carrier-shaft, and each spindle is journaled with its central part in bearings formed in the journal-plates and projects with its upper end upwardly through an opening in the supporting-plate d^3 , as shown in Figs. 3, 6, and 7. The die-sleeve c^2 , which surrounds the upper end of each die-spindle, rests on the upper side of the supporting-plate d^3 . Each of the several die-spindles is rotated on its own axis by a master gear-wheel G , meshing with gear-pinions g on the lower ends of the die-spindles, as shown in Figs. 3 and 6. The master gear-wheel G is secured to the upper end of a sleeve g' , which is mounted on the carrier-shaft above the lower bearing thereof, as shown in Fig. 6. g^2 is a driving-sleeve arranged on the driving-shaft and provided on its inner end with a bevel gear-wheel g^3 , which meshes with a bevel gear-wheel g^4 on the lower end of the sleeve g' . The outer end of the driving-sleeve g^2 is provided with a driving-pulley g^5 , which receives a driving-belt. The driving-sleeve is capable of moving lengthwise on the driving-shaft for engaging its gear-wheel g^3 with the gear-wheel g^4 or disengaging the same therefrom for rotating the die-spindles or stopping the rotation thereof. The longitudinal movement of the driving-sleeve is effected by a shifting-lever g^6 , connected with a collar g^7 , which is arranged in an annular groove in the driving-sleeve. The bevel gear-wheel f is shifted lengthwise on the driving-shaft into its operative or inoperative position at the same time that the gear-wheel g^3 is shifted into its operative or inoperative position by coupling-lugs g^8 , arranged on the inner side of the gear-wheel g^3 and engaging with an annular groove in the hub of the gear-wheel f . This means of driving the carrier and the dies cause these parts to be turned positively, thereby insuring turning of the buttons while acted upon by the buff-

ing-wheel, whereby burning or discoloring of the buttons is avoided, which otherwise would be liable to happen.

A vertically-reciprocating movement is imparted to each die-spindle for ejecting the button from the die after the same is polished.

When the dies are arranged on the front side of the carrier, the die-spindles are lowered, so that the concave seats in the upper ends thereof are arranged below the upper ends of the die-rings, as represented in Figs. 3 and 7.

When the dies are in this position the operator places the unpolished buttons upon the dies, each button resting with its convex under side against the concave top of the die-spindle and with its edge against the inner side of the ring, as represented in Figs. 3 and 7.

The dies, together with the unpolished buttons supported thereon, are carried bodily by the carrier around the axis of the latter in the direction of the arrow, Fig. 10,

and at the same time each die, together with the button supported thereon, rotates about its individual axis.

As the dies and buttons move along the rear side of the carrier the rotating buffing-wheel engages with its lower side against the top of the buttons, as represented in Fig. 3, and polishes the same.

After the buttons have passed the buffing-wheel, during the continued rotation of the carrier, the die-spindles are successively raised, so that the concave upper end of each spindle is arranged above the die-ring, whereby the polished button is lifted from the die-ring

preparatory to being removed therefrom by a discharging or sweeping device. The die-spindle is preferably lifted for ejecting the button thereon while the die is arranged on the left side of the carrier.

After the polished button has been removed from the die-spindle the latter is lowered into its operative position preparatory to receiving another unpolished button as it passes the front side of the machine.

The upward movement of the die-spindle is effected by a lifting-cam H , which is arranged in the path of the lower ends of the die-spindles, so that the latter, while moving bodily around the axis of the carrier, engage their lower ends successively with the lifting-cam and are thereby lifted for discharging the buttons thereon.

The cam is vertically adjustable, so as to permit the extent which the die-spindles are raised to be adjusted to suit the size or thickness of the buttons and also to compensate for any wear of the dies or the discharging device which removes the buttons from the dies.

For this purpose the lifting-cam is arranged on the upper end of a vertically-movable plate h , which is raised and lowered by a rock-finger h' , engaging between two lugs h^2 on the cam-plate.

The rock-finger is secured to a rock-sleeve h^3 , which passes through a vertical slot h^4 in the cam-plate, and is mounted on a horizontal arbor h^5 , which projects forwardly from the standard A^2 , as shown in Figs. 1, 2, 6, and 10.

The front end of the rock-sleeve is provided with a hand-wheel h^6 for turning the same. The cam-plate is held in its adjusted position by a clamping-screw nut h^7 , arranged on the threaded front end of the arbor and bearing against the front end of a rock-sleeve, and a clamping-screw h^8 , passing through a vertical slot h^9 in the cam-plate and entering the standard A^2 , as shown in Figs. 6 and 8. After the die-spindles clear the lifting-cam H the same drop by gravity into their lower operative position, the movement of the spindles in this direction being limited by shoulders h^{10} on the spindles engaging with the upper side of the lower journal-plate d' , as shown in Figs. 3 and 6. The teeth of the master gear-wheel G and of the pinions on the die-spindles are sufficiently long to prevent the same from becoming disengaged during the vertical movement of the spindles.

The die-rings are rotated by frictional contact with the die-spindles, and as these rings rest on the supporting-plate d^3 the latter becomes worn by the lower ends of the die-rings. By making the supporting-plate of the carrier separate from the journal-plates the supporting-plate when worn considerably can be easily removed and replaced by a new one without necessitating the renewal of the journal-plates which contain the bearings of the spindles.

The discharging device for removing the polished buttons from the dies consists, preferably, of a rotary brush I , which is arranged above the die-spindles at the place where the same are raised by the lifting-cam. This brush is turned so that its lower part moves outwardly, whereby the buttons when lifted into engagement with the brush are swept outwardly by the latter from the top of the die-spindle. The buttons which are removed from the dies are discharged into a spout i , whereby the buttons are conducted into a receptacle. The delivery-brush I is journaled in a bracket i' , secured to the upper bearing e of the carrier-shaft, as shown in Figs. 6 and 10. Motion is imparted to the delivery-brush by any suitable means—for instance, as shown in Figs. 1, 6, and 10, by means of a friction-wheel i^2 , which is rotated by engaging with the top of the supporting-plate, a pair of intermeshing gear-wheels i^3 , arranged on the friction-wheel shaft and a counter-shaft i^4 , and a pair of intermeshing bevel gear-wheels i^5 , secured to the brush and counter-shaft, as shown in Figs. 1, 6, and 10.

J represents a horizontal guard or retaining plate whereby the buttons are prevented from becoming displaced or dislodged from the dies by the suction or blast of the buffing-wheel while the buttons are carried forward and from the buffing-wheel. The retaining-plate has the shape shown in Fig. 11 and is arranged close to the top of the buttons on the receiving and delivery sides of the buffing-wheel, as shown in Fig. 6, so that the buttons are held on the dies and prevented

from being dislodged therefrom by the blast or suction of the buffing-wheel. The buttons are sometimes placed improperly by the operator on the dies, so that they project too far above the same. In order to prevent these misplaced buttons from being injured while passing underneath the retaining-plate and also to straighten the buttons in the dies, the retaining-plate is yieldingly supported, so as to permit the same to yield upwardly. The yielding support for this purpose shown in the drawings consists of vertical guide-rods j , connected at their lower ends to the retaining-plate and passing freely with their upper ends through lugs j' , arranged on the upper bearing of the carrier-shaft, and a spring j^2 , surrounding each guide-rod between the guide-lug and the top of the retaining-plate, as shown in Figs. 1, 3, 6, and 10. The downward movement of the retaining-plate is limited by screw-nuts j^3 , arranged on the upper screw-threaded ends of the guide-rods and bearing against the top of the guide-lugs. By screwing the nuts up or down on the guide-rods the position of the retaining-plate may be adjusted to suit different thicknesses of buttons or to compensate for the wear on the dies. The retaining-plate is centered on the carrier-shaft by a hook j^4 , arranged on the front part of the plate and embracing the carrier-shaft, and a cross-bar j^5 , which is secured across the opening of the hook so as to confine the retaining-plate on the carrier-shaft, as shown in Fig. 11. The retaining-plate is held against turning with the carrier, but is permitted to move vertically by a vertical pin j^6 , which is secured to a stationary table j^7 or other support arranged adjacent to the carrier and which projects upwardly through a perforated ear j^8 on the adjacent part of the retaining-plate, as shown in Figs. 6, 10, and 11.

For the purpose of permitting the buffing-wheel to be raised or lowered or moved backward or forward for adjusting the buffing-wheel to suit different sizes of buttons or for taking up wear of the wheel an adjusting mechanism is provided, which is constructed as follows:

K represent two upright supporting-arms provided at their upper ends with bearings k , in which one end of the shaft of the buffing-wheel is journaled. The lower ends of the supporting-arms K are arranged on opposite sides of the standard A^2 and are pivoted by horizontal screws k' to a cross-head k^2 . The latter is guided in vertical ways k^3 in the standard A^2 . By raising or lowering the cross-head k^2 the upper ends of the supporting-arms, together with the buffing-wheel mounted thereon, may be moved upward or downward, and by swinging the upper ends of the supporting-arms forward or backward, together with the buffing-wheel, the latter may be adjusted to the position which the size or character of the buttons require in order to buff or polish the same properly. The

vertical adjustment of the cross-head k^2 is effected by a vertical screw-shaft k^4 , which is journaled at its ends in bearings on the standard A^2 and which works in a screw-threaded opening in the cross-head k^2 , as shown in Fig. 9. The screw-shaft is turned in either direction for raising or lowering the cross-head by an upright shaft k^5 , journaled in bearings k^6 on the main frame and connected at its lower end with the screw-shaft by intermeshing gear-wheels k^7 , while its upper end is provided with a hand-wheel k^8 , as shown in Figs. 1, 6, 8, and 10.

L represents a horizontal screw-shaft whereby the buffing-wheel is adjusted backward or forward and which is arranged lengthwise on one side of the buffing-wheel. This shaft engages with its screw-threaded rear end in a swiveling screw-nut l , which is pivoted on a post l' , arranged on the rear part of the base. The screw-shaft L is journaled near its front end, but held against lengthwise movement in a swiveling bearing l^2 , which is pivoted on the upper end of one of the supporting-arms.

K. Upon turning the screw-shaft L in one direction or other the upper ends of the supporting-arms are moved backward or forward. The screw-shaft L is turned by means of a shifting-sleeve l^3 , which is provided with a hand-wheel l^4 and which is keyed or splined on the screw-shaft in front of its swiveling bearing l^2 by a pin l^5 on the shaft passing through longitudinal slots l^6 in the sleeve. The screw-shaft L is held in position after adjustment by a shoulder l^7 on the shaft bearing against the rear side of the swiveling bearing and a clamping-screw l^8 , which is arranged on the screw-threaded front end of the shaft and which presses the shifting-sleeve l^3 against the front side of the swiveling bearing l^2 , as shown in Fig. 12. The buffing-wheel is rotated in the direction of the arrow, Fig. 3, by a belt M, passing around a driving-pulley m on the driving-shaft m' and a pulley m^2 on the buffing-wheel shaft B' and also around intermediate pulleys m^3 m^4 . The intermediate pulley m^3 is mounted on a shaft m^5 , which is journaled in bearings arranged on arms m^6 , projecting rearwardly from the main standard A', as shown in Figs. 1 and 10. The other intermediate pulley m^4 is mounted on an upright adjusting-lever N, which is pivoted at its lower end, so that it can be swung forward or backward for adjusting the tension of the driving-belt M. The adjusting-lever is held in position after adjustment by a spring-catch n, pivoted on the lever and engaging with one of a longitudinal row of teeth n' on a horizontal catch-bar n^2 . The latter is pivoted at its rear end on the upper end of the post l' and rests with its front end on a lug or pin n^3 , arranged on the tightener-lever N, adjacent to the catch of the latter. Upon shifting the lever backward or forward the catch-bar rises or falls, so as to adjust itself to the changing position of the tightener-lever.

O represents a delivery pipe or conduit

whereby the particles of dust and dirt which are removed from the buttons while polishing the same are carried away. The buffing-wheel is arranged in the front end of this pipe and projects downwardly through the opening in the front end thereof into engagement with the buttons which are carried past the same. The buffing-wheel is detachably secured to its shaft between a collar p, fixed on the shaft and bearing against one side of the wheel, and a detachable collar p' , which is pressed against the opposite side of the wheel by a screw-nut p^2 on the shaft. In order to permit of conveniently applying the buffing-wheel to its shaft and removing the same therefrom, the front end of the dust-pipe is provided with a movable side portion o', which is arranged on one side of the buffing-wheel, and a movable top portion o^2 , which is arranged above the buffing-wheel. These movable sections are hinged at their rear ends to the main part of the dust-pipe, and when swung outwardly they form an opening in the top and side at the front end of the dust-pipe which affords access to the buffing-wheel.

Q represents a rotary fan which is arranged in an enlargement of the dust-pipe in rear of the buffing-wheel, as shown in Figs. 3 and 10, and which assists the buffing-wheel in conducting the dust rearwardly through the dust-pipe. The fan is mounted on the shaft m^5 of the intermediate pulley which extends across the dust-pipe, whereby the driving-belt M drives the buffing-wheel and fan at the same time and in the same direction.

For the purpose of waxing the buffing-wheel without requiring the attention of the operator an automatic waxing device is provided, which is constructed as follows:

R represents a gear-wheel which meshes with a gear-wheel R' on the upper end of the carrier-shaft and which is provided on its upper side with two wax-holders r. These wax-holders are rotated from the carrier-shaft by the gear-wheels R R' and are so arranged that each holder rubs the piece of wax which it holds against the periphery of the buffing-wheel at the receiving side thereof, thereby leaving the periphery of the buffing-wheel on the delivery side thereof unwaxed, whereby the buttons as they are carried past the buffing-wheel are first subjected to a harsh treatment for removing the dust and dirt therefrom and then receive a comparatively gentle treatment for finishing the face of the buttons. One wax-holder is preferably provided with wax containing grit which causes the buffing-wheel to produce an abrading action upon the buttons, while the other holder is provided with a piece of smooth wax which causes the buffing-wheel to produce a polishing action on the buttons. The gear-wheel R' , which carries the wax-holders, is journaled on a rock-arm r' , which is pivoted on the carrier-shaft, as represented in Figs. 1, 4, and 6, whereby these wax-holders may be adjusted toward and from the buffing-wheel for

taking up the wear on the wax or on the buffing-wheel without disturbing the driving-gear. The adjustment of the rock-arm r' is effected by an adjusting-rod r^2 , which is piv-

oted at its rear end to the rock-arm and passes with its front end loosely through a guide-lug r^3 on the upper bearing e , and screw-nuts r^4 r^5 , arranged on the adjusting-rod on opposite sides of the guide-lug r^6 , as shown in Figs. 1, 3 to 5, and 10.

It will be observed that the various adjusting devices are arranged within convenient reach of the operator while the latter stands at the front of the machine and permits of adjusting the several parts while the machine is running.

I claim as my invention—

1. The combination with the buffing-wheel, of a rotary carrier, rotary spindles journaled in said carrier parallel with the axis thereof and provided with button-supporting dies and with gear-pinions, and a driving gear-wheel journaled concentrically with the carrier and meshing with the inner sides of the gear-pinions of the spindles, substantially as set forth.

2. The combination with the buffing-wheel, of rotary spindles provided with button-supporting dies, a rotary carrier in which said spindles are journaled, an upright shaft on which the carrier is mounted, a horizontal driving-shaft having a bevel gear-wheel splined thereon which meshes with a similar gear-wheel at the lower end of the upright shaft, a master gear-wheel mounted on the upright shaft and meshing with pinions on the spindles, a driving-sleeve mounted on the driving-shaft and provided with a bevel gear-wheel which meshes with a similar gear-wheel connected with said master gear-wheel, a coupling connecting the bevel gear-wheels on the driving-shaft and driving-sleeve, and a shifting device whereby the bevel gear-wheels on the driving shaft and sleeve are shifted simultaneously into and out of engagement with the bevel gear-wheels of the upright shaft and the master gear-wheel, substantially as set forth.

3. The combination with the buffing-wheel, of a support, an upright spindle mounted on said support and provided at its upper end with a die face or seat for the under side of a button, a die-ring surrounding the upper end of the die-spindle and resting upon the support and engaging with the edge of the button, and means whereby a rotating and an axial movement is imparted to the die-spindle, substantially as set forth.

4. The combination with the button-buffing wheel, of a rotary carrier, upright spindles mounted on said carrier and each provided at its upper end with a die face or seat for the under side of the button, die-rings surrounding the upper ends of the die-spindles and resting upon the carrier and each ring provided with a die face or shoulder which engages with the edge of the button, a master or driving gear-wheel meshing with gear-pin-

ions on the spindles, and a cam which is engaged by the spindles while the latter move with the carrier and whereby the spindles are raised, substantially as set forth.

5. The combination with the button-buffing wheel, of a rotary carrier, upright spindles mounted on said carrier and each provided at its upper end with a die face or seat for the under side of the button, die-rings surrounding the upper ends of the die-spindles and resting upon the carrier and each ring provided with a die face or shoulder which engages with the edge of a button, a master or driving gear-wheel meshing with pinions on the spindles, a cam which is engaged by said spindles and whereby the latter are moved axially, an adjusting rock-arm whereby said cam is adjusted, and a clamping device whereby the cam and rock-arm are held in position, substantially as set forth.

6. The combination with a button-buffing wheel, of a rotary carrier provided with a removable supporting-plate, of die-spindles mounted on the carrier and extending through the supporting-plate, die-rings surrounding the upper ends of the spindles and resting on the supporting-plate, and means whereby a rotary and an axial movement is imparted to the spindles, substantially as set forth.

7. The combination with the button-buffing wheel, the rotary carrier and the button-supporting dies journaled in said carrier, of a rotary discharge-brush arranged above the path of the buttons on the dies, a friction-wheel which engages with the carrier and is rotated thereby, and an intermediate transmitting-gearing whereby the rotation of the friction-wheel is transmitted to the discharge-brush, substantially as set forth.

8. The combination with the button-buffing wheel, the dies which support the buttons, and the carrier upon which the dies are mounted and whereby the buttons are carried past said wheel, of a retaining-plate which extends over the buttons on the dies adjacent to the sides of the buffing-wheel and which prevents the buttons on the dies from being displaced by the blast of the buffing-wheel, substantially as set forth.

9. The combination with the button-buffing wheel, the dies which support the buttons, and the carrier upon which the dies are mounted and whereby the buttons are carried past said wheel, of a retaining-plate which extends over the buttons and the dies adjacent to the sides of the buffing-wheel, and an adjusting device whereby the retaining-plate may be adjusted toward and from the dies, substantially as set forth.

10. The combination with the button-buffing wheel, the dies which support the buttons, and the carrier upon which the dies are mounted and whereby the buttons are carried past said wheel, of a retaining-plate which extends over the buttons on the dies adjacent to the sides of the buffing-wheel, upright guide-rods secured to said plate and passing through sta-

tionary guide-lugs, springs which are interposed between the guide-lugs and the retaining-plate and which hold the latter in a depressed position, and adjusting screw-nuts 5 arranged on the upper ends of said rods and bearing against the upper sides of said lugs, substantially as set forth.

11. The combination with the buffing-wheel and the rotary carrier provided with button-10 supporting dies, of an upright rocking support which carries the buffing-wheel at its upper end, a vertically-adjustable cross-head to which the lower end of the rocking support is pivoted, and an adjusting device whereby 15 the rocking support is moved backward or forward, substantially as set forth.

12. The combination with the buffing-wheel and the rotary carrier provided with button-20 supporting dies, of an upright rocking support which carries the buffing-wheel at its upper end, a vertically-adjustable cross-head to which the lower end of the rocking support is pivoted, a vertical screw-shaft working in a threaded opening in said cross-head, an up-25 right shaft provided with a hand-wheel and connected with the screw-shaft by gearing, and an adjusting device whereby the rocking support may be moved backward or forward, substantially as set forth.

30 13. The combination with the buffing-wheel and the rotary carrier provided with button- supporting dies, of an upright rocking support which carries the buffing-wheel at its up- per end, a horizontal screw-shaft engaging

with its screw-threaded rear end in a nut 35 which swivels on a stationary support and is journaled at its front end in a bearing which swivels on the upper part of the rocking support, a collar or shoulder arranged on the screw-shaft and bearing against the rear side 40 of the swiveling bearing, a clamping-sleeve keyed on the screw-shaft and bearing against the front side of the swiveling bearing, and a clamping-screw arranged on the front end 45 of the screw-shaft and bearing against the front end of the clamping-sleeve, substantially as set forth.

14. The combination with a buffing-wheel, of a rotary wax-holder adapted to move past said buffing-wheel, and a driving mechanism 50 whereby said wax-holder is rotated, substantially as set forth.

15. The combination with the buffing-wheel and the button-supporting dies, of a driven gear-wheel arranged adjacent to the buffing-55 wheel and provided with a wax-holder, a driving gear-wheel meshing with said driven gear-wheel and mounted on a shaft, an arm pivoted on said shaft and carrying the driven gear-wheel, and an adjusting device connect- 60 ing said arm with a stationary support, substantially as set forth.

Witness my hand this 30th day of June, 1900.

JOHN A. SHOEMAKER.
